UNITED STATES PATENT OFFICE.

CARL E. DUNHAM, OF BAKER, NORTH DAKOTA.

DEVICE FOR HOLDING FLEXIBLE SPOUTS.

1,216,296.

Specification of Letters Patent. Patented Feb. 20, 1917.

Application filed July 29, 1916. Serial No. 112,092.

To all whom it may concern:

Be it known that I, CARL E. DUNHAM, a citizen of the United States, residing at Baker, in the county of Benson and State 5 of North Dakota, have invented certain new and useful Improvements in Devices for Holding Flexible Spouts, of which the following is a specification, reference being had to the accompanying drawings.

10 This invention relates to certain improvements in devices for holding flexible spouts and has relation more particularly to a device of this general character especially designed and adapted for use in connection with cars or the like; and it is an object of 15 the invention to provide a device of this general character having novel and improved means whereby the spout may be readily and conveniently adjusted in accordance with the requirements of practice and 20 whereby the loading of a car or the like may be materially facilitated.

The invention consists in the details of construction and in the combination and arrangement of the several parts of my improved device for holding flexible spouts whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view partly in elevation and partly in section illustrating a holding device for flexible spouts constructed in accordance with an embodiment of my invention;

Fig. 2 is a view partly in top plan and partly in section of the device as herein embodied;

Fig. 3 is a sectional view taken substantially on the line 3—3 of Fig. 1;

Fig. 4 is a fragmentary view partly in elevation and partly in section illustrating the clamping mechanism carried by the bracket and coacting with the supporting arm or rod;

Fig. 5 is a sectional view taken substan-

tially on the line 5—5 of Fig. 2 looking in the direction of the arrow;

55

Fig. 6 is an inner face view of one of the disks as herein embodied; and

Fig. 7 is a view in plan of the plate coacting with the loop of the pivot member.

As disclosed in the accompanying drawings, B denotes a bracket provided with the returned arms 1 whereby means is afforded for operatively engaging the bracket with the side of a car door or other support, and disposed through said arms 1 are the clamping members 2 to afford means whereby the bracket B may be positively maintained in applied position.

3 denotes a resilient plate having one end portion permanently secured to the bracket 70 B and having its opposite end portion returned, as at 4, the band of said returned portion 4 being formed into a barrel or sleeve 5 through which the elongated supporting arm or rod 6 is adapted to be disposed.

Disposed loosely through the returned portion 4 and in threaded engagement with the bracket B is the clamping member 7 provided with the head 8 adapted to coact with 80 the returned portion 4, whereby it will be perceived that upon rotation of the clamping member 7 in one direction, the supporting arm or rod 6 will be effectively clamped in its adjusted position either in longitudinal adjustment or in a rotary adjustment 85 about its longitudinal axis.

9 denotes a member substantially U-shape in form and having secured to the outer surface of one of its sides 10 a plate 11 returned, 90 as at 12, the bend of the plate 11 affording a barrel 14 adapted to receive the forward end portion of the elongated arm or rod 6 hereinbefore referred to whereby it will be perceived that the member 9 may be adjusted 95 about said arm or rod 6 in accordance with the requirements of practice.

15—15 denote two clamping disks having their opposed faces provided with the radial recesses 16 extending entirely thereacross 100 and adapted to register, and the axial center of said disks 15 are provided with the registering slots 17 intersecting the grooves or recesses 16 and disposed at right angles thereto.

105 The sides 10 of the member 9 are provided

with the alined openings 18 and 19, the opening 19 being continued through the connected portion of the plate 11 with the returned portion 12 of said plate being provided with an opening 20 adapted to register therewith. The opening 18 is of sufficient diameter to permit the insertion therethrough of the pivot member P which, as herein embodied, comprises an elongated loop 21 adapted to extend through the registering slots 17 and having its side members 22 spaced apart a distance sufficient to position said side members 22 at opposite sides of the registering grooves or recesses 16 so that no obstruction will be offered to the elongated member 23 when disposed between the disks 15 and within the registering recesses or grooves 16.

One end of the loop 21 is provided with the threaded extension 24 which extends through the openings 19 and 20 and is engageable with the clamping member 25 overlying the returned portion 12, whereby it will be perceived that upon movement being imparted to the loop 21 in one direction, the barrel 14 will be caused to clamp upon the arm or rod 6 to positively hold the member 9 in its adjusted position relative to the arm or rod 6.

The opposite end of the loop 21 is provided with the threaded recess 26 through which is disposed the operating member 27, the inner end of which being adapted for contact with the plate 28 arranged within the loop 21 and being provided with diametrically opposed peripheral recesses 29 to receive the side members 22 for a purpose which is believed to be self-evident. The plate 28 is substantially circular in plan and of a diameter in excess of the diameter of the opening 18, whereby it will be perceived that upon requisite rotation of the operating member 27, the requisite movement will be imparted to the loop 21 to effect the clamping action hereinbefore referred to.

The elongated member 23 has one extremity provided with the clamping band 30 adapted to be operatively engaged with the discharge extremity of a flexible spout, whereby it will be perceived that said spout may be adjusted as desired and effectively locked in its various adjusted positions.

From the foregoing description, it is thought to be obvious that a device for holding flexible spouts constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself

to the precise arrangement and formation of the several parts herein shown in carrying out my invention in practice.

I claim:

1. A device for adjustably holding a flexible spout comprising a bracket provided with attaching means, an elongated arm, means for adjustably securing the arm to the bracket, a supporting member, a split barrel carried by the member and adapted to receive an end portion of the arm whereby said member may be adjusted around the arm, a pivot member carried by the first named member and capable of endwise movement, said pivot member being provided with means coacting with the barrel for adjusting the same into clamping relation relative to the arm, means for imparting endwise movement to the pivot member, clamping disks carried by the pivot member, and an elongated spout engaging member disposed between the disks and adapted to be clampingly engaged thereby upon endwise movement of the pivot member in one direction. 70 75 80

2. A device for adjustably holding a flexible spout comprising a bracket provided with attaching means, an elongated arm, means for adjustably securing the arm to the bracket, a supporting member, a split barrel carried by the member and adapted to receive an end portion of the arm whereby said member may be adjusted around the arm, a pivot member carried by the first named member and capable of endwise movement, said pivot member being provided with means coacting with the barrel for adjusting the same into clamping relation relative to the arm, means for imparting endwise movement to the pivot member, clamping disks carried by the pivot member, and an elongated spout engaging member disposed between the disks and adapted to be clampingly engaged thereby upon endwise movement of the pivot member in one direction. 90 95 100 105 110

3. A device for adjustably supporting a flexible spout comprising an arm provided with attaching means, a U-shaped member rotatably engaged with the arm, a pivot member rotatably supported by the U-shaped member, said pivot member having its intermediate portion looped and provided with an extension, said extension being provided with means coacting with the clamping means of the U-shaped member for causing said clamping means to operatively engage the supporting arm, clamping disks having their opposed faces provided with radial grooves extending entirely thereacross and adapted to register, said disks being also provided with slots adapted to register and 115 120 125 130

10

arranged at right angles to the grooves and through which the pivot member is directed, the opposite end of the pivot member being provided with a threaded opening, and a member disposed through and operatively engaged with said threaded opening of the pivot member and coacting with the adjacent side of the U-shaped member for im-

parting movement to the pivot member in one direction.

In testimony whereof I hereunto affix my signature in the presence of two witnesses.

CARL E. DUNHAM.
